UNITED STATES PATENT OFFICE

2,085,986

DEEP WELL TURBINE PUMP

John M. Levier, Anaheim, Calif.

Application April 11, 1934, Serial No. 720,010

7 Claims. (Cl. 103—102)

This invention relates to deep well turbine pumps and particularly to such pumps and the casings thereof which are adapted to be used in crooked holes.

It is a matter of considerable difficulty, particularly in the case of a deep well, to drill a straight hole. In general, the subterranean water level in the United States is going down and the difficulty arising from crooked holes of substantial depth is increasing.

The principal object of the present invention is to provide an improved deep well turbine pump.

A further object of the invention is to provide a deep well turbine pump in which the outer casing, the drive shaft, and the drive shaft housing are suitably articulated to adapt them for use in holes having a considerable deviation from straightness, the elements referred to cooperating to maintain an efficient and non-leaking assembly.

A further object of the invention is to provide an improved lubrication system for deep well turbine pumps.

Other objects, advantages, and capabilities will appear from the following description of a preferred embodiment thereof, taken in conjunction with the accompanying drawings, in which

Figure 1 is a sectional view through the motor and associated parts at the top of the well, the preferred lubrication system being shown diagrammatically in this view;

Fig. 2 is a sectional view which may be regarded as a continuation of Fig. 1, showing typical joints of the casings and shaft and illustrating the manner in which they take care of deflection;

Fig. 3 is a sectional view showing the upper end of the turbine pump and associated parts, and may be regarded as an extension of Fig. 2 on a somewhat larger scale;

Fig. 4 is a sectional view showing the lower part of the turbine pump, and may be regarded as an extension of Fig. 3;

Fig. 5 is a sectional view of a well showing the whole pump assembly in operative relation thereto;

Fig. 6 is a sectional detail view, taken on the line 6—6 of Fig. 3, showing the complementary driving elements 41 and 52 in operative relation, and

Fig. 7 is a sectional view, taken on the line 7—7 of Fig. 6, the elements being separated for the purpose of clearness.

Referring to the drawings, the motor which drives the pump is indicated by the reference nu-

meral 10. This motor is mounted on a base 11 which includes the outlet 12 for the water pumped from the well. The well itself consists of an irregular hole, indicated at 13. Preferably at the top of the well is provided a block of concrete 14 having an opening in alignment with the hole 13.

The outer housing or casing comprises a plurality of lengths of pipe of suitable diameter, designated 15. These lengths of pipe are normally manufactured in ten foot lengths. It will be understood, however, that in order to take care of sharp angles at a particular location, I may use shorter lengths of pipes 15, and it will be understood that corresponding sections of the drive shaft and the drive shaft housing, hereinafter to be described, will be of approximately the same length, it being preferred that the articulation of the three elements, the outer housing, the drive shaft and the drive shaft housing, shall be located at substantially the same heights. The uppermost pipe section 15 of the main housing is

threaded into the base 11 so that it communicates with the water outlet 12. At its lower end the pipe section 15 has secured thereto, preferably by screwing it onto its threaded end, a ring 16, the outer surface of which is spherical and adapted to cooperate with the corresponding surface of a ring 17 which is secured to the length of the pipe by the mounting of the ring 16 thereon. The rings 16 and 17 constitute ball and socket joints providing for a limited articulation in all directions. The ring 17 is bolted to a flanged ring 18, a suitable gasket 19 being interposed therebetween. This ring 18 is threadedly mounted on the next lower pipe section 15 which, in turn, carries at its lower end another ring 16. The number of such universal joints and the number of pipe sections 15 employed, will depend upon the depth to which the housing must extend to obtain water.

Each ring 17 is provided on its inner spherical surface with an annular groove which receives packing material 20. This packing material is of somewhat greater volume than the groove in which it is located so that when tension is applied to the casing as a whole the packing material 20 will be compressed tightly against the adjacent ring 16 and leakage from the outer housing will thereby be effectively prevented.

The lowermost housing section 15 is connected by a similar universal joint with a relatively short section of pipe 21 of the same diameter. At its lower end the pipe 21 is rigidly secured to the turbine pump 22 which will now be described.

The pipe 21 carries at its lower end the flanged

collar 23 which is bolted to the upper flange of the pump 22. The pump 22 comprises rotors 24 suitably located within rotor chambers and having an outlet 25 at the upper end whereby water 5 is forced into the casing formed by the pipe sections 15. Below the rotors 24 the pump 22 is provided with a water receiving chamber 25, the wall of which is provided with lateral openings 26 whereby the water enters. The spindle 27 of the 10 turbine pump carries the rotors 24 and extends through the chamber 25 into a bearing chamber 28 therebelow. A gland 29 is provided in the wall between the chambers 25 and 28 so as to prevent leakage from one chamber to the other. The 15 chamber 28 may suitably be bolted to the lower end of the chamber 25 and it includes a thrust bearing 30 upon which the lower end of the shaft 27 is mounted. At its lower end the shaft 27 has mounted thereon a shouldered collar 31 which 20 rests on the thrust bearing 30.

Mounted on the lower end of the housing 28 is a downwardly projecting chamber 32 which is utilized for a supply of oil for the bearing 30, which oil is supplied by a pipe 33 which will hereinafter be more fully described in connection 25 with the oiling system. A pipe 34 also enters the chamber 32 and is provided with an internal extension 35 which terminates near the bottom of the chamber 32 so that any water or sludge 30 which may leak into or which may form in the chamber 28 can be withdrawn to the surface.

The upper portion of the pump shaft 27 extends upwardly through a packing gland 36 which is contained within tubular elements 37 and 38. 35 The former is threadedly mounted on the upper end of the pump 22 and the tubular member 38, which is of somewhat larger diameter than the tubular member 37, is threadedly mounted on the tubular member 37. The packing material of the 40 gland 36 is contained within the tubular member 38 and is compressed by means of a spring 39, also located within the tubular member 38. The tubular member 38 has threaded thereinto a bearing sleeve 40 which provides an abutment for 45 the spring 39. The bearing sleeve 40 is an element which is provided in all the joints of the housing and it will be described in detail in connection therewith. The upper end of the shaft 27 has threaded thereon a universal driving element 50 41, regarding which the same remarks apply.

The construction of the drive shaft and the drive shaft housing, with particular reference to a point of articulation, will now be described. 55 The drive shaft housing comprises a plurality of sections 42, the upper ends of which are threadedly connected to a sleeve 40, which sleeve has the same external diameter as the housing section 42. The upper end of the sleeve 40 is 60 internally stepped so as to receive a bearing bushing 43. The drive shaft comprises a series of sections 44 which are substantially the same length as the pipe sections 42 and 15. At their upper ends they are threaded to receive universal driving elements 41. The lower edge of the driving element 41 rests upon a flange at the upper end of the bushing 43 so that the weight of the drive shaft is communicated thereby to the drive shaft housing. The next superior drive shaft 65 housing section 42 rests upon the upper end of the sleeve 40. Where there is no angular deviation the lower end of the last named section 42 abuts upon the upper end of the sleeve 40. When, however, there is an angular deviation, there is 70 a space between the lower end of the housing 75

section 42 and the upper end of the sleeve 40 except at one point where they touch. An outer sleeve 45 is arranged so as to extend over the sleeve 40 and over the ends of both sections 42 adjacent thereto, this sleeve being of somewhat greater diameter than the pipe sections 42 or sleeves 40, so as to provide for the deviation referred to.

Each end of the sleeve 45 is flared so as to provide an annular pocket for the reception of 10 packing material 46. This packing material is compressed by flanges of packing rings 47 which are located around the pipe sections 42. The packing rings 47 at each end are compressed together by means of rods 48 which extend through 15 the bores in the sleeve 45. The sleeve 45 is formed as an integral part of a spider 49, the outer diameter of which is substantially the same as the internal diameter of the ring 48 so that the spider may move freely within the ring 48 to a limited 20 extent.

The driving element 41 is recessed on its upper face, as indicated at 50. This recess is provided with internal teeth 51 so that it may operatively be engaged by the complementary toothed 25 element 52 which is in the form of a small gear cut upon the lower end of a short shaft 53. The teeth 52 are provided with a certain amount of camber in the longitudinal direction so that they may cooperate with teeth 51 of the driving elements 41 within the degree of deflection which it is intended to provide. The short shafts 53 are rigidly mounted, for example by means of couplings 54, upon the lower threaded ends of the shaft sections 44. Short shafts 53 increase the 30 effective lengths of the shaft sections 44 so as to correspond with the increase of length provided in the drive shaft casing by the provision between the pipe sections 42 of the sleeve 40 and in the main or outer casing by the elements which connect adjacent pipe sections 15. It will readily be understood that if the shaft sections 44 were made slightly longer the driving elements 52 could be directly mounted thereon. I prefer to provide small openings 51a in the driving elements 41 to permit lubricant and sediment to escape from the recesses 50.

The shaft 55 of the motor 10 projects downwardly into the drive shaft housing and at its lower end is operatively connected to the adjacent drive shaft section in the same manner as the drive shaft sections are operatively connected. The uppermost pipe section 42 of the drive shaft housing extends freely through an opening 56 in the upper wall of the water outlet 12. Leakage of water is prevented by means of packing 57 located therearound. A plate 58 is threaded onto the upper projecting end of the uppermost pipe section 42 and a gland 59 is mounted thereon so as to prevent escape of oil from the drive shaft 60 housing. Stud bolts 60 mounted in the head casting project upwardly through openings in the plate 58. By tightening nuts 61 on the stud bolts 60 pressure may be applied upon the plate 58, which pressure is communicated all along the 65 elements constituting the drive shaft housing, the pressure eventually becoming exerted upon the stationary portion of the pump 22. As indicated above, the elements constituting the drive shaft housing have a certain freedom of longitudinal 70 movement with respect to the elements constituting the main housing. Consequently, the pressure applied to the pump 22 will result in tension being applied upon the elements constituting the main or outer housing. The result of this ten- 75

sion is to apply pressure which forces the rings 17 downwardly with respect to the rings 16. In this way the packing rings 20 are strongly compressed at the points of articulation and the result is that a water-tight main housing is provided, irrespective of the depth to which the housing may go. This sealing effect is also accentuated by the weight of the drive shaft housing and also by the weight of the drive shaft elements which, as has been pointed out above, are carried by the drive shaft housing. The sealing effect is also accentuated by the weight of the water within the casing when the pump is being operated.

15 The lubricating system will now be described. For the purpose of lubricating the drive shaft elements throughout their length, oil is supplied by a pipe 62 into the uppermost pipe section 42 of the drive shaft housing. This oil passes downwardly through the drive shaft housing lubricating all the driving elements and bearings therein. For the purpose of facilitating the downward passage of the oil, it is preferred to provide a plurality of ducts 63 in each of the sleeves 40. The oil is eventually arrested by the packing 36 immediately above the pump 22. The oil is adapted to pass from the tubular member 38 through a flexible metal tube 64 which passes upwardly between the drive shaft housing and the main housing, passing through the openings in the spiders 49. The flexible metal tube 64 terminates at the top of the well and is connected to a nipple 65 mounted in the casting 11. The nipple 65 is connected to an exterior tube 66.

35 The flexible tubes 33 and 34, which connect into the oil reservoir 32 as previously described, extend upwardly on the outer side of the pump 22, being protected from injury by a cover plate 67. These pipes terminate adjacent the upper end of the pipe section 21 and communicate through suitable connections thereon with flexible pipes 68 and 69. These flexible pipes extend upwardly throughout the length of the main casing between the main casing and the drive shaft casing, in the same manner as the pipe 64. The pipe 68 is connected to a nipple 70 and the pipe 69 is connected to a nipple 71. These nipples extend to the outer side of the water outlet in the same manner as the nipple 65 previously described, and are connected respectively to flexible pipes 72 and 73.

The pipe 62 receives oil from a tank 74, which oil preferably passes through an oil filter 75 and a sight feed gauge 76. The supply of oil to the pipe 62 is controlled by means of a valve 77. This oil which passes downwardly through the drive shaft housing, as described above, emerges by pipe 66 and may be drawn off at a regulated rate by means of a valve 78. The pipe 66 may, however, communicate with another oil tank 79, and a valve 80 enables this supply to be regulated at will. The oil tank 79 is connected to the pipe 72 and a valve 81 is provided in this pipe to control the supply of oil. The oil thus supplied descends downwardly between the housings, being carried through pipe 68, from which it passes to pipe 33 which empties into chamber 32. Oil, together with any water, sludge or dirt, passes upwardly through pipes 35, 34, 69 and 73, the rate of the outlet being controlled by means of a valve 82. In order to apply automatically an appropriate degree of pressure to the oil system which will prevent entrance of the water into the drive shaft housing or into the thrust bearing compartment 28, by means of leakage through the glands

and joints, I prefer to provide a water pipe 83 which communicates with the water outlet of the pump and with a water tank 84. The upper end of the water tank is placed into communication with the upper end of the oil tank 74 by means of a pipe 85 containing a valve 86. It will readily be understood that when the pump is working at high pressure, the pressure of the water is applied to the tanks 74 and 79 and that the whole oiling system is maintained under a substantial pressure. This pressure, of course, will be greater at progressively lower points in the well on account of the head of oil above these points.

In installing the improved pump, it will be understood that the well is drilled and that a survey is made to determine upon points where considerable angular deviation will be located. If necessary, special short lengths may be employed to meet individual circumstances. In general, however, standard lengths of pipes and shafts are used whenever possible. The whole device is assembled from the bottom up, that is, the pump and its connections are first arranged and adjusted. The pump is lowered into the well and additional sections are built on as are required. Lastly, the topmost sections are secured to the casting 11 and finally the motor is mounted thereon. It is to be noted that the pump shaft 27 is adjusted at the bottom by means of the step collar 31 so as to bring the rotors 24 into exact position. This is done before the pump is installed in the well, by means of the nuts on either side of the step collar 31.

During the assembly anchor chains 87 are secured to the rings 17 and to the pipe sections 15 above them, for the purpose of limiting the amount of rotation which may take place between adjacent pipe sections 15 and between the lowermost pipe section 15 and the pump unit.

Although the invention has been disclosed in connection with the specific details of a preferred embodiment thereof, it must be understood that such details are not intended to be limitative of the invention except in so far as set forth in the accompanying claims.

Having thus described my invention, what I claim as new and desire to secure by Letters Patent of the United States is:

1. In a deep well turbine pump assembly, in combination, an outer casing, a drive shaft and drive shaft housing therein, said outer casing comprising pipe sections and ball and socket connections between them providing free deflection at said connections between adjacent sections, means adjacent said ball and socket connections providing articulation in the drive shaft and drive shaft housing, and means for applying compressive force upon said drive shaft housing whereby said outer casing is subjected to tension and the ball and socket connections are held in liquid-tight relation.

2. In a deep well turbine pump assembly, in combination, an outer casing formed of pipe sections, a housing within said casing rigidly connected thereto at top and bottom, ball and socket connectors between said pipe sections providing free articulation therebetween at said connections, packing means associated with said ball and socket connectors, means adjacent said ball and socket connections providing articulation in the drive shaft and drive shaft housing, and means for applying compressive force to said inner housing whereby tension is applied to the

outer casing and said packing is compressed to establish water-tight joints.

3. In a deep well turbine pump assembly, an outer casing, a drive shaft and drive shaft housing all formed of sections of substantially the same length, ball and socket elements connecting the outer casing sections providing a certain amount of deflection at said connecting elements between adjacent sections, spacer elements adjacent said ball and socket elements and freely slidable relative thereto, said spacer elements receiving adjacent ends of drive shaft housing sections freely to permit a certain amount of deflection between adjacent sections at said spacer elements, and packing means associated with said spacer elements for maintaining water-tight relation between the interior and exterior of the housing.

4. In a deep well turbine pump assembly, an outer casing, a drive shaft and drive shaft housing all formed of sections, ball and socket elements connecting the outer casing sections providing a certain amount of deflection between adjacent sections, spacer elements adjacent said ball and socket elements and freely slidable relative thereto, said spacer elements receiving adjacent ends of drive shaft housing sections, at least one of said ends having a free fit with respect to said spacer element so as to permit a certain amount of deflection therebetween, packing means associated with said spacer elements for maintaining water-tight relation between the interior and exterior of the housing, sleeves secured to said housing sections, and driving connections secured to said shaft sections, said connections resting on said sleeves whereby the weight of the driving shaft is transferred to the drive shaft housing along its length.

5. A deep well turbine pump assembly, comprising a deep well turbine pump, a drive shaft therefor extending from the surface, a drive shaft housing, a main outer casing, said shaft, housing and casing being formed of sections of substan-

tially the same length and having ball and socket members forming the connection between adjacent casing sections to provide a certain degree of deflection between adjacent casing sections at said connections, bearings carried by said housing at the adjacent ends of the housing and casing sections for said shaft sections, and means adjacent the ball and socket means providing articulation in the drive shaft and drive shaft housing.

6. In a deep well turbine pump assembly, an outer casing, a drive shaft and drive shaft housing all formed of sections of substantially the same length and having adjacent connections to provide a certain amount of deflection between adjacent sections at said connections, the connections for the outer casing being ball and socket joints, sleeves associated with said ball and socket joints overlapping adjacent drive shaft housing sections, packing means between the sleeves and drive shaft housing sections, and internal and external gear elements operatively establishing the connection between adjacent drive shaft sections.

7. In a deep well turbine pump assembly, an outer casing, a drive shaft and drive shaft housing all formed of sections of substantially the same length and having adjacent connections to provide a certain amount of deflection between adjacent sections at said connections, the connections for the outer casing sections being ball and socket joints, sleeves located adjacent said ball and socket joints overlapping said drive shaft housing sections, packing means between the sleeves and drive shaft housing sections, internal and external gear elements operatively establishing the connection between adjacent drive shaft sections, and a sleeve rigidly carried by each drive shaft housing section, one of said gear elements overhanging the associated last said sleeve, whereby the weight of the drive shaft section is transferred to the last said sleeve.

JOHN M. LEVIER.
